PANIC EXIT CASE

John R. Foster, Indianapolis, Ind., assignor to Vonnegut
Hardware Company, Indianapolis, Ind., a corporation of Indiana

Filed Apr. 18, 1963, Ser. No. 74,498

Term of patent 14 years

(Cl. D10—8)

FIG. 1 is a side elevational view of a panic exit case embodying my new design;

FIG. 2 is a front elevational view thereof;

FIG. 3 is a bottom plan view thereof; and

FIG. 4 is a reduced, side elevational view as seen from the right of FIG. 2.

I claim:

The ornamental design for a panic exit case, as shown.
